US0D1002999S

(12) United States Design Patent (10) Patent No.: US D1,002,999 S
(45) Date of Patent: * Oct. 31, 2023

(54) PAIR OF PANTS

(71) Applicant: Shelby Group International, Inc.,
Collierville, TN (US)

(72) Inventor: Shawn Norfolk, McKinney, TX (US)

(73) Assignee: Shelby Group International, Inc.,
Collierville, TN (US)

() Term: 15 Years

(21) Appl. No.: 29/797,841

(22) Filed: Jul. 2, 2021

(51) LOC (14) Cl. 02-02

(52) U.S. Cl. USPC D2/742

(57) CLAIM

The ornamental design for a pair of pants, as shown and described.

DESCRIPTION

FIG. 1 is a front perspective view of the pants according to the present invention.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines shown in the figures are for the purpose of illustrating portions of the pants which form no part of the claimed design.

1 Claim, 6 Drawing Sheets
